United States Patent Office.

FREDERICK WESSEL, OF NEW BRITAIN, CONNECTICUT.

Design No. 4,256, dated July 19, 1870.

DESIGN FOR A BRACELET.

The Schedule referred to in these Letters Patent and making part of the same.

I, FREDERICK WESSEL, of New Britain, in the county of Hartford and State of Connecticut, have invented and produced a new and original Design for a Bracelet, of which the following is a specification.

The design for a bracelet shown in the accompanying drawings consists of a thin sheet of suitable metal, with a roll upon each edge.

Figure 1 is a perspective view of a bracelet of my design, and

Figure 2, a sectional view of the same.

A designates the band which forms the body of the bracelet, and

a a designates a roll, formed on each edge of the band A, a section of which is shown in fig. 2.

The bracelet is divided into two parts, which are hinged together at b, and fastened by a clasp at c.

The band A may be carved or ornamented, as desired.

I claim as my invention—

The herein-described design for a bracelet, consisting of the band A, with a roll, a a, upon both of its edges, substantially as shown and described.

FREDERICK WESSEL.
